FOREIGN PATENT DOCUMENTS

CN 201730195452 * 5/1917

Primary Examiner — Anhdao Doan

(57) **CLAIM**

The ornamental design for an automatic external defibrillator training device, as shown and described.

DESCRIPTION

FIG. 1 is a perspective top view of an automatic external defibrillator training device showing our new design;
FIG. 2 is a perspective bottom view thereof;
FIG. 3 is a top view thereof;
FIG. 4 is a bottom view thereof;
FIG. 5 is a left side view thereof;
FIG. 6 is a right side view thereof;
FIG. 7 is a front end view thereof; and,
FIG. 8 is a rear end view thereof.

The broken lines in the drawings are included for the purpose of illustrating portions of the defibrillator that form no part of the claimed design.

1 Claim, 5 Drawing Sheets
